UNITED STATES PATENT OFFICE.

AUGUSTE L. SALTMAN, OF EAST ORANGE, NEW JERSEY, ASSIGNEE, BY MESNE ASSIGNMENTS, TO NEW JERSEY PATENT COMPANY, OF WEST ORANGE, NEW JERSEY, A CORPORATION OF NEW JERSEY.

PRIMARY PATENT.

1,087,143.

Specification of Letters Patent. Patented Feb. 17, 1914.

Application filed October 4, 1911. Serial No. 882,302.

To all whom it may concern:

Be it known that I, AUGUSTE L. SALTMAN, a citizen of the United States, and a resident of East Orange, in the county of Essex and State of New Jersey, have invented certain new and useful Improvements in Primary Batteries, of which the following is a specification.

My invention relates generally to improvements in primary or voltaic batteries, and more particularly to that class of batteries in which the negative electrode consists of a plate of oxid of copper, or other depolarizing agent, properly molded or aggregated, and the positive electrode of a plate or plates of zinc, and in which both the positive and negative elements are supported by a frame or hanger which is adapted to be suspended from the battery jar cover by a single suspension means such as a rod or bolt, whereby the electrodes and their supporting frame or hanger may be easily removed as a unitary structure for any desirable purpose, such as cleaning or renewals.

The object of my invention is to improve the construction of batteries of this type and more particularly to provide a simple and efficient connection between the rod, bolt or other suspension means and the supporting frame or hanger, whereby the rod, bolt or other suspension means is held in place in the supporting frame or hanger when the electrodes and their supporting structure are removed from the jar cover, and also to provide a construction which permits the easy removal of the rod or bolt from the frame or hanger when desired. My improved construction provides an efficient mechanical connection and good electrical contact between the bolt or rod and the supporting frame or hanger.

My invention consists further in the details of construction and combinations of parts hereinafter more particularly described and claimed.

In the accompanying drawings which form a part of this specification and in which like reference characters refer to like parts in the several views—

Figure 1 is a side elevation, partly in section, of a portion of a battery embodying my invention; Fig. 2 is a vertical section with top and bottom broken away on a

line through the middle of Fig. 1, and at 55 right angles thereto, and showing also the zincs and their supporting blocks; Fig. 3 is a plan view, partly in section, on the line 3-3 of Fig. 1; Figs. 4 and 5 are views in elevation of the lower portion of the supporting rod or bolt employed in the embodiment of my invention illustrated in Figs. 1, 2 and 3, the said views being on a larger scale than Figs. 1, 2 and 3. Fig. 6 is a vertical sectional view of a portion 65 of a battery in which a modified construction is shown; and Fig. 7 is a vertical section of a portion of a battery showing another modification.

Referring to the drawings, the cover of 70 the battery jar is shown at 1.

The numeral 2 indicates a frame or hanger preferably constructed of a strip of sheet copper or copper plated iron or steel, the edges of said strip being turned up to 75 such an extent as to lie flat against the bevel edges of the negative electrode plate 3. The plate 3 is preferably of copper oxid. The cross section of the hanger 2 is channel shaped, as is clearly shown in Figs. 2, 80 6, and 7. The hanger 2 is preferably given the form of an inverted U and engages the bevel edges of the negative plate 3. The said plate 3 fits into the channel of the hanger 2 and is held in said hanger by any 85 suitable supporting means as, for example, by a rod 4 extended through openings in the lower ends of the depending arms of the hanger and held in place by an upturned portion 4' of the rod and a nut 4''. The 90 upturned lips 2' of the frame 2 assist in properly positioning and supporting the rod 4 and the plate 3. The hanger 2 has a horizontal cross portion or piece 5, which is provided with depending lips 6 having 95 openings therein preferably trapezoidal or tapered in shape and registering with a similar opening in the plate 3. The horizontal cross portion or piece 5 of the hanger is provided with upwardly extended portions 7 having inwardly extended lugs or projections 8 as is clearly shown in section in Figs. 2, 3, 6, and 7. The upwardly extended portions 7 having the inwardly extended lugs or projections 8 are preferably 100 formed of the material partly cut out between the lips 6 when the frame is stamped out, and bent or forced into the form de-

scribed and illustrated. In this manner a slotted structure is provided above the horizontal cross portion of the frame and forming a part thereof.

- 5 My invention is not limited to the form of frame or hanger illustrated, but is applicable to any form of frame or hanger which is provided with a cross portion, cross piece or bridging member adapted to 10 have formed upon it or secured to it a slotted structure of the character described. If desired, the frame 2 may be constructed of separate pieces of sheet metal secured together in any suitable manner.
- 15 The zinc or positive electrode plates of the battery indicated at 9 and 10 are secured to an insulating block or blocks 11 and to the horizontal cross portion of the frame by a suitable bolt 12. The bolt 12 is provided 20 with a head 22 and a nut 23 and with conducting washers 24 and 25, the washer 24 being located between the zinc plate 9 and the nut 23 and the washer 25 being located between the end of the conducting lead 26 25 and the zinc plate 10, the end of the conducting lead 26 being held in place between the head 22 of the bolt and the washer 25. Thus, the zinc plates are supported from the horizontal cross portion of the frame, and 30 the battery plates and their supporting frame form a unitary structure adapted to be supported from the jar cover by a single rod, bolt or other suspension means.

As a means for supporting the frame and the battery plates and the jar cover, I make use of a suitable rod or bolt 13 which is preferably screw threaded and which is provided with a head 14 preferably block-shaped. The head 14 of the bolt 13 is adapted to be 40 slipped into the slotted structure formed by the upwardly extended members 7 having the inward projections 8. A nut 15 is provided for the screw threaded rod 13 for clamping the inwardly extended projections 45 8 between the same and the head 14 of the said rod or bolt. The inwardly extended projections 8 may extend into recesses 16 in the stem of the bolt, as is clearly shown in Figs. 2 and 3, or may simply engage and 50 overlap the head 14 of the bolt, as is shown in Figs. 6 and 7. The nut 15, the head 14, and the slotted structure formed by the upwardly extended portions of the frame constitute a simple and efficient means for 55 clamping the supporting bolt or rod to the supporting frame or hanger of the battery plates. A suitable sleeve 17 may be interposed between the nut 15 and another nut 18 threaded upon the stem of the rod or 60 bolt and which preferably engages the underside of the battery jar cover for giving additional stiffness to the suspension means. Obviously, my improved structure is adapted for use with a battery jar cover having

a depending perforated portion. When such a battery jar cover is used, the sleeve 17 and the nut 18 are dispensed with. Wing nuts 19 and 20 may be provided for the stem of the bolt above the jar cover to clamp the structure to the battery jar cover 70 and to provide a convenient means for attaching a conducting wire to the negative element of the battery.

In order to provide additional stiffness and rigidity in the connection between the 75 rod or bolt and the frame, a channel-shaped member 21, such as is shown in Fig. 7, may be employed. The depending side portions of this channel-shaped member assist in clamping the upturned portions 7 and inwardly extended projections 8 to the head of the rod or bolt. It will be observed that I have provided a simple and efficient means for securing an adequate mechanical connection and good electrical contact between 80 the supporting bolt or rod and the frame or hanger at an imperforate portion of the frame or hanger.

Having now described my invention, what I claim as new and desire to protect 90 by Letters Patent of the United States is as follows:—

1. In a voltaic battery, the combination with positive and negative elements, of a frame for supporting the said elements, a 95 supporting member adapted to be supported from the battery jar cover, and means for securing the said supporting member to the said frame at an imperforate portion of the said frame, substantially as described. 100

2. In a voltaic battery, the combination with positive and negative elements, of a frame for supporting the said elements, a supporting member adapted to be supported from the battery jar cover, and means for 105 securing the said supporting member to the said frame at an imperforate portion of the said frame, said means being operable to permit detachment and attachment of said member from and to said frame, substantially as described. 110

3. In a voltaic battery, the combination with positive and negative elements, of a frame for supporting said elements and having a cross piece, a supporting member 115 adapted to be supported from the battery jar cover, and means for securing the said supporting member to an imperforate portion of said cross piece, substantially as described. 120

4. In a voltaic battery, the combination with positive and negative elements, of a frame for supporting said elements and having a cross piece, a supporting member adapted to be supported from the battery 125 jar cover, and means for securing the said supporting member to an imperforate portion of said cross piece, said means being op-

erable to permit detachment and attachment of said member from and to said cross piece, substantially as described.

5. In a voltaic battery, a supporting frame having a channel shaped cross piece or portion, portions of the walls of the channel being upturned and inturned to form a slotted structure, and a member having a head adapted to be secured within the slotted structure, substantially as described.

6. In a voltaic battery, a supporting frame having a channel shaped cross piece or portion, portions of the walls of the channel being upturned and inturned to form a slotted structure, a member having a head adapted to be received within the slotted structure, and means for clamping the said structure to the said headed member, substantially as described.

20. 7. In a voltaic battery, the combination with a negative plate, of a frame for engaging edge portions of said plate and including a channel cross portion, a single supporting rod adapted to be supported from the battery jar cover, and means for securing the said supporting rod to the said frame at an imperforate portion of the channel cross portion, substantially as described.

8. In a voltaic battery, the combination 30 with a negative plate, of a frame for engaging edge portions of said plate and including a channel cross portion, a single supporting rod adapted to be supported from the battery jar cover, and means for securing the said supporting rod to the said frame at an imperforate portion of the channel cross portion, said means including a nut coöperating with said rod and operable to permit detachment of said rod from said 40 frame, substantially as described.

9. In a voltaic battery, the combination with a negative plate, of a frame for engaging edge portions of said plate and including a channel cross piece having upwardly 45 extended members at an imperforate portion thereof, a single supporting headed member adapted to be supported from the battery jar cover, and means for securing the said headed member to the said frame

at the imperforate portion of the said channel cross portion and including the said upwardly extended members and means for clamping the same to the said headed member, substantially as described.

10. In a voltaic battery, the combination 55 with a negative plate, of a frame for engaging edge portions of said plate and including a channel cross piece having upwardly extended members at an imperforate portion thereof, a single supporting headed 60 member adapted to be supported from the battery jar cover, and means for securing the said headed member to the said frame at the imperforate portion of the said channel cross portion and including the said upwardly 65 extended members and a nut for clamping the same to the said headed member at the headed end thereof, substantially as described.

11. In a voltaic battery, the combination 70 with a negative plate, of a frame for engaging edge portions of said plate and including a channel cross portion, a single supporting rod adapted to be supported from the battery jar cover, the said channel cross 75 portion having upwardly extended members for engagement with the supporting rod, and means for clamping the upwardly extended members to the said rod, whereby the said frame and plate are supported by 80 the said rod, substantially as described.

12. In a voltaic battery, the combination with a battery element, of a frame for supporting the said element and having a channel-shaped cross-piece with depending walls 85 and with portions of the walls upturned, a supporting member adapted to be supported from the battery jar cover, and means for clamping said supporting member to the upturned portions of the walls of the cross- 90 piece, substantially as described.

This specification signed and witnessed this 2nd day of October, 1911.

AUGUSTE L. SALTZMAN.
